Primary Examiner — Martie K Holtje(74) *Attorney, Agent, or Firm* — Peter L. Brewer; Baker Donelson(57) **CLAIM**

We claim the ornamental design for a handheld transceiver with display, as shown and described.

DESCRIPTION

FIG. 1 is a right front perspective view of a handheld transmitter with display showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The features shown in broken lines depict portions of the handheld transceiver with display that form no part of the claimed design.
